UNITED STATES PATENT OFFICE.

CARL BARR, OF CHICAGO, ILLINOIS.

ELECTRIC SWITCH.

1,251,856.

Specification of Letters Patent.

Patented Jan. 1, 1918.

Application filed March 26, 1917. Serial No. 157,333.

To all whom it may concern:

Be it known that I, CARL BARR, a citizen of the United States, residing at Chicago, in the county of Cook and State of Illinois, 5 have invented certain new and useful Improvements in Electric Switches, of which the following is a specification.

My invention relates to electric switches and has for its primary object the provision 10 of an improved clip for coöperation with the knife of an ordinary knife switch in order to complete or break an electric circuit.

A further object of my invention is the provision of a clip which shall be extremely 15 cheap to manufacture and so simple in construction as to require a minimum of labor in mounting the same.

Other objects and advantages of my invention will appear from the following description taken in conjunction with the accompanying drawings which form a part of this specification.

In the drawings

Figure 1 is a view in perspective of my 25 improved switch illustrating the clip thereof in full lines and the blade and its mounting in dotted lines;

Fig. 2 is a side elevation of my invention illustrating a modified form, and

Fig. 3 is a top plan view of the device shown in Fig. 2.

Reference numeral 10 indicates any suitable mounting for the blade 11 of my improved switch, the blade being pivoted as at 35 12 in any suitable manner to the mounting. Fig. 1 illustrates a form of my invention in which the blade is adapted to move in a plane angled with respect to the surface of the base plate or other insulating board (not 40 shown) to which the switch is attached; while Figs. 2 and 3 illustrate a form in which the blade moves parallel to the surface of the insulating board. It will be understood that the blade 11 is of any suitable 45 form such as is commonly used in knife switches: preferably, however, it comprises a plain strip of sheet copper or sheet brass.

The clip portion of my invention comprises a strip of sheet brass or similar electricity conducting material which, adjacent one end is upset in a die to form a finger 14, the edges of the strip 13 remaining intact after the finger 14 is upset, in order that a sufficient body of material may be left to 55 oppose the pressure of the finger 14 against the blade 11. The upsetting of the finger

14 from the strip 13 leaves two substantially parallel edge pieces 15 and 16 of the strip intact and across the end of the strip an edge piece 17 which integrally unites the side edge 60 pieces 15 and 16. The pieces 15, 16 and 17 together form a back to receive the thrust of the finger 14 when the blade 11 is interposed between the finger and the back. Preferably the ends of the finger 14 and the back 65 are bent away from each other, as best illustrated in Fig. 1, to guide the descending blade 11 into the space provided between the finger 14 and the back. In the upsetting of the finger 14 the finger is upset at the bottom 70 where it joins the strip substantially as far from the side pieces 15 and 16 as the thickness of the blade 11 to be employed, while the upper free end of the finger 14 is bent inwardly toward the back pieces 15, 16 75 and 17, so that the upper end of the finger is nearer the upper ends of the side edge pieces 15, 16 than the thickness of the blade 11 to be used. Inasmuch as the strip 13 is made of resilient material the entry of the 80 blade 11 between the finger 14 and the back of the clip will cause an intimate contact between the finger and back and the respective sides of the blade 11. By leaving side edge pieces 15 and 16 I obtain a balancing 85 of the pressure on opposite sides of the blade, whereas the constant use of the switch would tend to bend the blade, making it more difficult to insert it in the clip, if the clip had not a side edge piece opposing the 90 finger at each of its edges. At its lower end the strip 13 may be bent to form a mounting 18 apertured as at 19 for passage of a fastening screw, or any other suitable securing device. If desired, however, the strip 95 may be merely apertured, as at 19 in Fig. 2, to enable it to lie flat against the insulating board upon which it is mounted instead of causing it to stand at an angle to the board, as in Fig. 1.

100 The operation of my improved switch will be obvious to anyone who has read the foregoing description and seen the drawings, it being plain that the blade 11 is mounted to oscillate in a plane which will cause it to 105 enter between the finger 14 and the back of the clip.

While I have illustrated and described the preferred embodiment of my invention, it is obvious that one skilled in the art may 110 make modifications thereof without departing from the spirit of the invention. I wish,

therefore, not to be restricted to the precise embodiment shown except in so far as the same is limited in the appended claim.

I claim:

A clip comprising the unbroken marginal portion only of a strip of resilient metal, and a resilient metal finger attached by one end to said strip, positioned opposite the in-

terior aperture of said marginal portion, spaced from the plane of the strip and approaching said plane at its free end, the tip of said end receding from the strip and the strip being bent away from said tip.

In testimony whereof I have affixed my signature.

CARL BARR.
